UNITED STATES PATENT OFFICE.

LEWIS GIBBS, OF CANTON, OHIO.

GANG-PLOW.

SPECIFICATION forming part of Letters Patent No. 402,155, dated April 30, 1889.

Application filed August 9, 1888. Serial No. 282,346. (No model.)

To all whom it may concern:

Be it known that I, LEWIS GIBBS, a citizen of the United States, and a resident of Canton, county of Stark, State of Ohio, have invented a new and useful Improvement in Gang-Plows, of which the following is a full, clear, and exact description, reference being had to the accompanying drawings, making part of this specification.

10 My invention relates to improvements in gang-plows; and it consists in providing a light and substantial plow-supporting frame, a caster-wheel-supporting frame secured to the rear thereof, guide-wheel supported on cranked axle-shaft composed of two sections, and means for rotating said axles independently of each other and for securing them in a rigid relation for co-operation.

With these ends in view my invention consists of certain features of construction and combination of parts, as will be hereinafter described, and pointed out in the claims.

Figure 1 is an isometrical view of a gang-plow, illustrating my invention. Fig. 2 is a plan view of same. Fig. 3 is same view of guide-wheel-axle shaft. Fig. 4 is an isometrical view of hand-lever; Fig. 5, same view of coupling-sleeve and locking-rack.

Similar letters of reference indicate corresponding parts in all of the figures of the accompanying drawings.

A represents the plows, B and B' the beams, which are secured in parallel relation and spaced apart by braces, as C, and strut D. 35 To the rear portion of beam B is secured a frame, E, in which the supporting-arm F of caster-wheel G is pivotally secured, and may be adjusted vertically on the shaft a, and secured in adjustment by the set-screws b. The shaft a is supported in journal-boxes c in the rear portion of frame E.

The plow-supporting frame is formed of the beams B and B', braces, as C, and a strut, D. The front portion of said frame is supported 45 upon and pivotally secured to the axles H and H' by means of the hangers J, said hangers having at their lower ends journal-boxes f, in which the axle-shafts H and H' are loosely secured, said axles having crank portions p and spindles q, on which the guide-wheels K and K' are loosely secured.

A sleeve, as L, is provided, in which the in-

ner ends of the axle-shafts H and H' are placed. That portion of the axle designated as H' is secured in said sleeve L by set-screws 55 g, and that portion designated as H is loosely secured therein, as shown in Fig. 3. On the free end of the sleeve L there is provided an outwardly-projected sector, h, having radial rack-teeth i, and an arm, j, having an elongated aperture, k, with serrations l.

To the arm j a hand-lever, M, is adjustably secured, and to secure said lever in desired adjustment, an upwardly-projected sector, O, the lower end secured to the beam B, said sector having rack-teeth m, and on said lever M is provided a spring-actuated locking-bolt, n, to engage the teeth m.

On the axle H is secured a hand-lever, N, having a spring-actuated locking-bolt, o, to engage the rack-teeth i, by which the axle-shaft H may be secured to the sleeve L and form a means of rotation independently of the axle H', and when thus locked both of the axles H and H' may be rocked by the lever M simultaneously in their pivotal connection with the plow-supporting frame to raise and lower the front end of the frame, and thereby change the pitch of the plow; or the locking-bolt o may be disengaged, and by use of the lever 75 N the axle H may be rocked independently of the axle H', by which movements the cranked portions p and spindles q of the axles H and H' may be brought into alignment or thrown out of alignment, as shown in Figs. 1 and 2, 85 to drop the guide-wheel K onto the bottom of the furrow.

The operation is as follows: In starting to plow the hand-lever N is thrown forward to bring the wheel-spindles in alignment, and in 90 which position they remain during the first round, having been adjusted by the lever M to regulate the depth of furrow. After this round the wheel K is dropped by use of the lever N to the bottom of the furrow, as shown 95 in Fig. 1, the locking-bolt engaging the teeth i. The axle-shafts are secured together, and, as hereinbefore stated, may be rocked simultaneously by the lever M to regulate the depth of furrow. It will be noticed that the plows 100 are supported on the wheels G and K K', and may be carried above ground by depressing the lever M, by which the spindles q and wheels K K' may be brought to a position sub-

stantially vertically below the central portion of the axle-shaft.

Having thus fully described the nature and pointed out the object of my invention, what I claim, and desire to secure by Letters Patent, is—

1. The combination, with a plow-frame consisting of the suitably-connected beams B B', of a two-part axle, H H', journaled in bearings pivotally secured to said frame, a coupling-sleeve, L, in which the two-part axle is secured, one of the parts of the said two-part axle being free to turn in said sleeve, while the other part of the two-part axle is fixed to said sleeve, a segmental rack, h, secured to said sleeve, and a locking-lever, N, to engage the said segmental rack and lock the parts of the two-part axle to each other, substantially as set forth.
2. The coupling-sleeve L, having a segmental rack portion, g, and a laterally-extending arm, J, provided with a vertical aperture and rows of serrations arranged at the sides of said aperture, substantially as set forth.
3. The combination, with a plow-supporting frame, of a supporting axle-shaft composed of two sections, as B and B', secured to said frame in journal-boxes and adapted to be rocked in said journals simultaneously or separately, said axles having cranked portions p and guide-wheel spindles q, a coupling-sleeve secured to axle H', said sleeve having an outwardly-projected arm, j, to which a hand-lever, M, is secured, by which the axle-shaft H' may be rocked in its piv-

otal connections to the beam B', a rack, O, and means for securing said lever and axle in desired adjustment, substantially as described, and for the purpose set forth.

4. The combination, with a plow-supporting frame composed, essentially, of the beams B B', spaced apart and secured in parallel relation, of a supporting axle-shaft composed of two portions, as H and H', pivotally secured to said frame, said axle portion having crank portions, as p and spindles q, a coupling-sleeve, L, secured to the inner end of said portion H', said sleeve having a rack portion, h, and an outwardly-projected arm, j, a hand-lever, M, secured thereto, a rack, O, and means of adjustably securing said lever to said rack, and a hand-lever, N, secured to axle portion H, the end of said axle loosely secured in sleeve L, and means for locking said lever in engagement with said coupling-sleeve, the lever M, to rock the axles H and H' simultaneously when said axles are locked in rigid relation to raise and lower the plow-supporting frame, and the lever N, to rock the axle portion H independently of the axle H', to adjust the wheel K to the furrow, substantially as described, and for the purpose set forth.

In testimony whereof I have hereunto set my hand this 16th day of July, A. D. 1888.

LEWIS GIBBS.
